UNITED STATES PATENT OFFICE

WILLIAM C. BANKS, OF JERSEY CITY, NEW JERSEY

THIRD RAIL PROTECTOR BRACKET

Application filed August 5, 1930. Serial No. 473,187.

This invention relates to an improved bracket for supporting the wooden protector strips or boards which overlie the third or power rail of an electric railway, and the same is in the nature of an improvement over prior United States Letters Patent No. 1,532,836, granted April 7, 1925.

The brackets employed for this purpose which are now in general use and which are commonly of the type disclosed in the patent above referred to, are open to the objection that they can be properly used in connection with track rails of one size only, thereby requiring a different sized bracket for each size of track rail. Obviously, this is a tremendous disadvantage in event the size of the track rails is changed after the third or power rail protectors have been installed, in that it necessitates a complete removal of the third or power rail installation in order to change the size of the brackets.

The present invention aims primarily to overcome the above recited objections and disadvantages by providing an improved bracket which is adjustable in height to accommodate itself to all of the different standard sizes of track rails either before or after installation of the brackets, and in the latter case without affecting the third rail installation.

The invention further aims to provide an improved adjustable third rail protector bracket which has not been unduly complicated and the cost of production of which has not been materially increased over those now in use, and in which the adjustment thereof may be readily accomplished either before or after installation.

With the above recited and other objects in view, reference is had to the following description and accompanying drawings, in which there is exhibited one example or embodiment of the invention, while the claims define the actual scope of the same.

In the drawings:

Figure 1 is a side view of the improved protector bracket in its installed position, parts being broken away and shown in section to disclose the underlying structure.

Figure 2 is a vertical sectional view taken

approximately on the line indicated at 2—2 in Figure 1.

Figure 3 is a horizontal sectional view taken approximately on the line indicated at 3—3 in Figure 1.

Referring to the drawings by characters of reference, the bracket includes a base A, an upper superposed overlying bracket arm B, and a shank designated generally by the reference character C, the base A being designed for attachment to a tie of a railway, the terminal B being adapted to support the protector strip or board which overlies the third rail, and the shank C forming a connection between the base and terminal.

In order to construct the bracket so as to render the same capable of use in connection with track rails of varying standard sizes, the shank portion C includes upper and lower sections 5 and 6, which are of the usual channel shaped configuration in cross section and which are designed to nest one with the other.

The lower section 6, which is preferably formed integral with the base A, is provided with a series of vertically spaced openings or slots 7, while the upper section 5 is formed with a tongue 8 which is designed to be selectively received by the openings or slots 7, for the purpose of increasing or decreasing the height of the shank C to coincide with the different sizes of track rails used. In order to lock the sections 5 and 6 in their vertically adjusted positions, said sections are provided with a series of registerable bolt receiving

openings 9 and 10 for a bolt 11 and a nut 12. In Figure 1 of the drawings, there are illustrated in full and dotted lines two of the relative positions of the sections 5 and 6 to disclose the manner in which the terminal B is adjusted. It thus follows that brackets constructed in the manner set forth may be initially adjusted to the desired height to coincide with the size of track rail used, and, further, that in event of a change in the size of the track rails after installation of the third rail and its protectors and brackets, the said brackets may be adjusted to compensate to the new size track rails without affecting the installation of the third rail.

While there has been illustrated and described a preferred form of the manner in which the bracket is rendered adjustable, it is to be clearly understood that no limitation is necessarily made to the precise structural details, and that variations and modifications which properly fall within the scope of the claims may be resorted to when desired.

What is claimed is:

10. 1. In a bracket for third rail protector strips, a base having an integral upstanding shank portion, an overlying terminal portion to which the protector strip is secured having an integral depending shank portion and means for connecting said upstanding and depending shank portions for vertical adjustment.
15. 2. In a bracket for third rail protector strips, a vertical channel shaped shank including a pair of telescopically associated sections, one of said sections having a series of vertical openings and a tongue formed on the other section selectively engageable in said openings.
20. 3. In a bracket for third rail protector strips, a vertical channel shaped shank including a pair of telescopically associated sections, one of said sections having a series of vertical openings and a tongue formed on the other section selectively engageable in said openings and means for locking said shank sections in vertically adjusted relation against separation.
25. 4. In a bracket for third rail protector strips, a vertical channel shaped shank including a pair of telescopically associated sections, one of said sections having a series of vertical openings and a tongue formed on the other section selectively engageable in said openings and means for locking said shank sections in vertically adjusted relation against separation, said means including registering openings in the shank sections and a bolt adapted to be selectively received by said openings.
30. 5. In a bracket for third rail protector strips, a base having an upstanding shank portion and an overlying terminal portion to which the protector strip is secured, said terminal portion having a depending shank portion and means for connecting said upstanding and depending shank portions for vertical adjustment.
35. 6. A bracket for supporting third rail protector strips in superposed relation to a third rail, including a shank element depending from said protector strip, a second shank element supported at its lower end and extending upwardly alongside of the third rail and means for connecting said shank elements for vertical adjustment to permit of the adjustment of the protector strip relative to the third rail whereby to compensate for variation in the height of the third rail used.
